Ms. 1156

Wm. Newton Brown, of New York, N.Y.
Letter Patent No. 716,016, dated Oct. 23, 1891.

The schedule referred to in this Letter Patent and marking part of the same.

To all whom it may concern:

Be it known that of Wm. Newton Brown of the City, County, and State of New York, have invented or produced a new and ornamental device for ornamenting the frame work of a Sewing Machine, and I do hereby declare the following to be a full description of the same, reference being had to the accompanying drawings forming a part of this specification, the same letters of reference wherever they occur referring to like parts.

Figure 1. is a side view of the machine, showing the ornamental device for the cloth presser lever, and spool holder.

Fig. 2. is a reverse side view of the machine showing the ornamental devices for the needle operator, and spool holder.

Letter A, is the frame of the machine having a serpined draught.

b, forming the sides of it, for the purpose of concealing the lever and feed motion spindles.

Letter c. is the cloth pressure lever.

This lever is ornamented by a serpent like device d, hatched or striped by intersecting lines, so as to represent scales. The head of the serpent forms the cloth pad e, and the tail by its elevation at the back end of the lever, a standard to support or hold a tension spool or roller f, for graduating the supply of thread unwound from the thread spool g. —

This spool is supported on a spindle held by female figures h, i. with averted faces and flowing hair, attached to opposite sides of the box at the back end of the machine, containing the propelling apparatus. These figures are nude to their waists, which are covered by several folds of drapery j. & k, the ends of which falling over one leg conceals it from sight, while the other from the middle of the thigh downwards is left exposed.

In the figure h, the arms are elevated above the head, and distended, the right hand is represented as holding the spindle on which runs the spool of thread, while the other holds a fillet of the thread, in the attitude of unwinding. In figure i, the left arm is elevated only, as engaged in holding the other end of the spindle, while the other arm is foreshortened against the side so that the hand rests upon a tension spring m, to give it the appearance of graduating the tension of the spring.

Letter n, is a needle-bar lever, having its outer end ornamented by a device representing a Sea Nymph, or mermaid p, having a wreath of seaweeds q, encircling its brows, its body bent gracefully forward, and upwards, and tail elevated above the line of the lever, at about midway of its length, through the points of which are holes for the passage of the thread.

The left arm is folded up across the breast, so as to bring the hand upon the right shoulder, through the fingers of which the thread passes to the point of the needle or. This needle is held by the shank, by the right hand s, which hangs down as if in the act of pointing or thrusting the needle through the cloth. —

Having now described my ornamental devices for ornamenting Sewing Machines, I will proceed to set forth what I claim and desire to secure by letters patent of the United States.

What I claim is the use of the combination and application of the devices herein before described, for ornamenting the frame and working parts of sewing machinery as set forth. —
